(57) **CLAIM**

We claim the ornamental design for an oblong belt-clip case, as shown and described.

DESCRIPTION

FIG. 1 is an isometric view of an oblong belt-clip case for carrying an oblong health tracker module.

FIG. 2 is a further isometric view of the oblong belt-clip case.

FIG. 3 is a side view of the oblong belt-clip case.

FIG. 4 is a top view of the oblong belt-clip case.

FIG. 5 is an opposing side view of the oblong belt-clip case.

FIG. 6 is a bottom view of the oblong belt-clip case.

FIG. 7 is a front view of the oblong belt-clip case.

FIG. 8 is a back view of the oblong belt-clip case.

FIG. 9 is an isometric view of the oblong belt-clip case with the oblong health tracker module inserted; and,

FIG. 10 is a top view of the oblong belt-clip case with the oblong health tracker module inserted.

Dashed and dotted lines are used for illustrative purposes only to give environmental context to the claimed design and do not form any part of the claimed design.

Stipple shading is used in FIGS. 1 through 10; the stipple shading is not to be understood as conveying a particular surface finish. The surface finish may be smooth/gloss, satin, or textured. The depicted articles may be made using materials of various colors, including black, charcoal, white, dark blue, lime, magenta, and other colors.

The oblong health tracker module may be inserted into the large cavity visible in the oblong belt-clip case of FIGS. 1 through 8, as shown in FIGS. 9 and 10, and worn on a person's belt or clothing
